ROCK OR MINERAL WOOL MANUFACTURE

Clinton L. Savidge, Toledo, Ohio, assignor to Ohio
Insulation Company, Toledo, Ohio, a corpora-
tion of Ohio

Application March 8, 1937, Serial No. 129,721

3 Claims. (Cl. 83—91)

This invention relates to forming and treating filaments in so-called rock wool manufacture.

This invention has utility especially in continuous manufacture from fusing to threading and placing the product into merchantable shape, say as mineral wool.

Referring to the drawing:

Fig. 1 is a section near the discharge portion of a fusing chamber or cupola showing an embodiment of the invention from the fused flow to the filament forming nozzle;

Fig. 2 is a section on the line X—X, Fig. 1, showing the relation of the flow or spreader plate to the nozzles and adjustable mountings.

Raw material descends in cupola 3 having 15 water jacketed sides 4. This cupola 3 is carried on frame members 5 supported by corner columns 6. Pressure blast 7 promotes combustion to fusing temperature in the cupola 3 to such extent that as the mass descends to fire brick lined region 8, there may be a molten, fused, or liquid mass 9 to flow over floor 10 having thickened outward ledge 11. Rising from this floor 10 is wall 12 having offset 13 from the forward or outward edges of the ledge 11. This wall 12 provides 20 bounds for port 14 flush with the floor 10 and with height above that of the molten mass 9 providing gas blow region 15 over flow 16 of the molten siliceous mass. This floor, ledge, and wall structure 10, 11, 12, may be desirably of metal, such as cast iron, with sufficient body to withstand the temperature and flow and contribute materially to the life of the cupola.

Angle iron 17 forward from the ledge provides mounting by means of bolts 18 for plate 19 having projection 20. Anchored with the frame 5 by bolts 21 are slotted arms 22 having bolts 23 to engage slots 24 in the angle iron 17. There is thus permitted desired adjustment for locating portion 25 from the plate 19 as a stream divider directly below the stream 16, for dividing such molten flow that approximately even portions thereof may pass down the respective inclines to drop 27 therefrom. With the contour herein disclosed there is a maintenance factor for continuity of operation and effective response in increasing flow-off of the melt from the cupola and effectively caring for such melt by pressure nozzle filament-forming action so effective transversely of such descending portions 27 as to completely and fully intercept the flow.

Herein steam lines 28 extend under the cupola and have offsets 29 toward each other with threaded upwardly directed termini 30, on which may be located caps 31 each having V-nozzle 32 55

therein for providing said pressure channel of steam as an effective carrier and filament producer in blowing into or across a descending melt 27. There is formed, transversely of the stream, 5 a filament mass 33. Supporting each steam pipe 28 is rod 34 having anchor 35 therewith, such rod having handle 36, and remote therefrom, stem portion 37 in an opening 38 of a strap 39 from the frame 5. Each rod 34, adjacent the handle, has weight 40 as a load against casual disturbance. One grasping the handle and thrusting such toward the nozzle may thereby adjust the height of the nozzle as to the stream 27 as the pipes 28 are slightly off horizontal. If there be occasion to adjust the nozzle more nicely into the stream laterally thereof, this is effected by pushing or pulling on the handle 36, in thereby thrusting the terminal 37 further into the opening 38 or withdrawing such slightly. This means that as to each nozzle there is a nicety of accurate control by a single handle for the multiple positions of the nozzle as to the descending melt.

The multiple blasts 33 are herein shown as upwardly directed.

The disclosure herein is one of manufacturing efficiency of importance in the insulation field and permits the economical production of a high grade product with efficiency in melting, in gathering, and placing into merchantable shape of a product having superior attributes.

In the operations hereunder, the step of charging the cupola is such as to maintain the flow bed of say 1 inch depth for the stream 16 in flow through a port 14, say 1 inch wide and 2½ inches high, the blast thereover being such as not to carry impurities. This flow stream of mass to be shredded has such divided for efficient shred or thread forming by the V-shaped pressure channels, say of steam.

40 What is claimed and it is desired to secure by United States Letters Patent is:

1. In a mineral wool manufacturing installation embodying means for flowing a stream of molten mineral wool forming material, a nozzle adjustably positioned to discharge a fluid under pressure against said stream for breaking up the stream into fibers, means for adjusting said nozzle transversely and longitudinally relatively to said stream comprising a single handle connected to said nozzle, and means for supporting the handle for movement in two directions at right angles to each other.

2. An attachment for a furnace comprising a pipe, a movable nozzle connected to the pipe and positioned for directing a jet of gaseous fluid on

a stream of molten materials flowing from the furnace for shredding the stream of molten materials into fibers, an actuating member, means for supporting the actuating member, said actuating member being swingable and longitudinally slidable relatively to the supporting means, and means for operatively connecting the actuating member with the nozzle for adjustably positioning the nozzle relatively to the stream of molten materials when the actuating member is swingably or slidably moved.

3. An attachment for a furnace comprising a pipe, a movable nozzle connected to the pipe and

positioned for directing a jet of gaseous fluid on a stream of molten materials flowing from the furnace for shredding the stream of molten materials into fibers, an actuating member, means

5 for supporting the actuating member, said actuating member being longitudinally slidable and otherwise additionally movable relatively to the supporting means, and means for operatively connecting the actuating member with the nozzle for adjustably positioning the nozzle relatively to the stream of molten materials when the actuating member is slidably or otherwise moved.

CLINTON L. SAVIDGE.
